F. L. G. STRAUBEL

PEDESTALED DESK

Filed Aug. 21, 1922

UNITED STATES PATENT OFFICE.

FREDERICK L. G. STRAUBEL, OF GREEN BAY, WISCONSIN.

PEDESTALED DESK.

Application filed August 21, 1922. Serial No. 583,096.

To all whom it may concern:

Be it known that I, FREDERICK L. G. STRAUBEL, a citizen of the United States, residing at Green Bay, in the county of Brown 5 and State of Wisconsin, have invented certain new and useful Improvements in a Pedestaled Desk; and I do hereby declare the following to be a full, clear, and exact description of the invention, such as will enable others skilled in the art to which it 10 pertains to make and use the same.

My invention relates to desks of the general class in which the table or top is detachable from its supports, and in one of its 15 general objects aims to provide a novel interlocking arrangement for detachably securing the table top to one or more pedestals. Furthermore, it aims to provide the interlocking arrangement in a simple and inexpensive construction which will require no 20 tools for manipulating the same and which will readily permit one and the same table top to be used interchangeably with a variety of pedestals. It also aims to provide an 25 interlocking arrangement of this general class which can readily be employed on table tops regardless of whether or not these tops have drawers secured to the same, and in one aspect aims to provide an interlocking 30 arrangement in which the runner supporting a drawer also affords at least a part of the desired interlocking. Still further and also more detailed objects will appear from the following specification and from 35 the accompanying drawings, in which—

Fig. 1 is a perspective view of a four legged double pedestal desk, showing the same as it appears when the table top has been interlocked with one of the pedestals 40 and is about to be interlocked with the other pedestal.

Fig. 2 is an enlarged central, longitudinal and vertical section through a desk similar to Fig. 1 but having simple legs in place of 45 the pedestal at the left hand side of the desk.

Fig. 3 is a section through a desk similar to Fig. 2 but having no drawer carried by the table top;

50 Fig. 4 is an enlarged and fragmentary perspective view showing the under side of the table top of Figs. 1 and 2 and the upper portion of the right hand pedestal of the same figures.

Fig. 5 is a fragmentary enlargement of the 55 middle upper portion of Fig. 2, showing the arrangement of the interlocking elements.

Fig. 6 is a fragmentary bottom view of the table top of Fig. 3, showing the arrangement of the interlocking elements on the 60 same.

While my invention may be employed with equal facility in connection with desks having various types of upper portions and with desks varying also as to the number of legs, it is particularly suitable for use with 65 flat top pedestaled desks having only four legs. I am therefore illustrating and describing it particularly in such four legged and flat topped embodiments, although I do 70 not wish to be limited to such uses of the same.

Referring first to the embodiments of Figs. 1 and 4, these relate to a flat top table in which the table top 1 is detachably mounted on a pair of pedestals disposed respectively under opposite ends of the table, and in which a drawer 2 is supported below the middle of the table by Z-shaped steel runners 3 secured to the bottom of the table top. 75 Each of the pedestals has a pair of end legs 4 and desirably is interlocked with the table top against sliding movement by dowels 5 projecting downwardly from the table top and entering corresponding socketing bores 80 6 disposed in the top of the pedestal, these dowel sockets being desirably in the end frame of the pedestal.

To cooperate with the said dowels in interlocking the table top with each pedestal, 90 I provide each pedestal with a pair of metal cleats 7 which desirably are secured to the top of the inner side of each pedestal and are so disposed as to project beyond the pedestal towards the middle of the table. Then 95 I provide the table top on its lower face with corresponding recesses 8 each of which is adapted to receive and house one of the said cleats while permitting that cleat to rest upon the upper horizontal web of the 100 adjacent Z-shaped runner 3. For this purpose, the recess 8 desirably extends somewhat further towards the adjacent end of the table top than the corresponding end of the cleat which is normally housed by that 105 recess, as shown in Fig. 5, thereby permitting the slidable insertion of the cleat into the corresponding recess when the table top

and the pedestal are relatively tilted as shown in Fig. 1. When both of the recesses 8 adjacent to one of the drawer-supporting runners are thus simultaneously entered by 5 the corresponding cleats, the subsequent downward swinging of the table top (or corresponding outward swinging of the pedestal) will cause each of the cleats to be housed by the adjacent recess while permitting 10 the table top to bear flatwise on the top of the pedestal, and the simultaneous entry of the dowels 5 into the sockets 6 will then hold the table top against sliding upon the pedestal.

15 When the parts are thus assembled, it will be evident from the drawings that the weight of the table top continually tends to swing the detachable pedestal of Fig. 2 in a counter-clockwise direction about the substantially pivotal engagement which the cleats 7 have with the upper edge of the strip 3 when the parts were being assembled. At the same time, the fastening of the 20 runner 3 to the under side of the table top, 25 which fastening can easily be made adequately strong for this purpose, will prevent any tendency towards having the pedestal rock about the upper edge of its end. The resulting assembly is therefore quite 30 firm and stable, although the desk can readily be taken apart whenever it may be desired to move the same through a narrow door or to handle the desk more easily when its owner moves from one location to 35 another.

Furthermore, pedestals of a given dimension but with different drawer arrangements, corresponding for example to the two drawer arrangements shown in Fig. 1, 40 can readily be used interchangeably with the same table top. Likewise, table tops with different upper surfaces can readily be used interchangeably with the same pedestals. Consequently, my arrangement permits both 45 the manufacturer and the dealer to assemble a wide variety of desks from a relatively small stock of the constituent parts, thereby greatly reducing both the investment and the storage space as compared with that 50 which would be required for the corresponding desks if constructed in the customary manner with rigidly attached pedestals. So also, since no tools whatever are required 55 for attaching or detaching the pedestals from the tops, this can readily be done by inexperienced persons and at a decided saving in this over that which would be required for screwing or otherwise fastening the corresponding parts to one another. My 60 invention is therefore a time saver also, although not involving any appreciable increase in the manufacturing cost over the older constructions.

However, while I have illustrated and 65 described my invention as employed in em-

bodiments of a highly desirable shape, I do not wish to be limited to the details of the construction and arrangement thus disclosed, it being obvious that the same might be modified in many ways without departing either from the spirit of my invention or from the appended claims. For example, it is immaterial for the purposes of my invention whether or not the upper or cleat-engaging ledge of the runner 3 of Figs. 1, 75 2 and 4 also carries a lower drawer-supporting portion. Where no drawer 2 is to be employed, I can therefore accomplish my purpose by securing a simple bar 9 to the lower face of the table top after the manner 80 of Fig. 3.

I claim as my invention:

1. In a table or desk, a top, a pedestal section at one end of the top to support said end thereof, means to support the other end of the top, said top having recesses on its under face, a drawer runner secured to said under face of the table top and extending transversely across each of the recesses, and cleats carried by the pedestal section and extending beyond the inner side of the latter, the cleats being receivable in the respective recesses to engage on top of the parts of the runner which traverse the recesses so as to be capable of pivotal movement relative to the runner, the first named end of the top and the outer side of the pedestal section having dowel and socket connections to hold the top and pedestal section against relative longitudinal movement.

2. In a table or desk, a top, a pedestal section at one end of the top to support said end of the top, means to support the other end of the top, said top having recesses on its under face, members carried by the inner side of the pedestal section and receivable in the respective recesses, an element common to each of the recesses and traversing the latter and engageable with said members to provide a detachable and pivotal connection between the top and pedestal section, and means between the top and pedestal section for holding said parts against relative longitudinal movement and being releasable upon relative pivotal movement of the parts.

3. In a table or desk, a top, a pedestal section for supporting one end of the table top having floor engaging means at its outer side only, means at the other end of the top for supporting the latter end, means at the inner side of the pedestal section for detachably and pivotally connecting the top to the pedestal section formed to require relative tilting between the top and pedestal section to connect and disconnect the said pedestal section from the top and means between the top and section to prevent relative longitudinal movement between the parts.

4. In a table or a desk having a pedestal

section and a drawer separate from the pedestal section, common means for supporting a side of the drawer and for connecting the pedestal section with the top; said common means comprising a substantially Z-shaped runner secured to the underside of the top and having its lower web underhanging the drawer and its upper web extending towards the pedestal; the top having recesses on its under face extending transversely across the said upper web of

the runner, the pedestal section having rigid elements projecting therefrom transversely of the said web and above the latter and each normally housed by one of the said recesses, 15 so as to compel a tilting of the pedestal with respect to the top before the said elements can be inserted into or withdrawn from the recesses.

Signed at Green Bay, Wisconsin, Aug. 20
7th, 1922.

FREDERICK L. G. STRAUBEL.
